UNITED STATES PATENT OFFICE.

PHILIP CAMELI, OF WILMINGTON, DELAWARE.

ADJUSTABLE SWITCH-POINT RAIL-SECTION.

1,344,259.

Specification of Letters Patent. Patented June 22, 1920.

Application filed November 22, 1919. Serial No. 339,797.

To all whom it may concern:

Be it known that I, PHILIP CAMELI, a citizen of the United States of America, residing at Wilmington, in the county of New Castle and State of Delaware, have invented certain new and useful Improvements in Adjustable Switch-Point Rail-Sections, of which the following is a specification.

The primary object of the present invention resides in the provision of devices associated with switch point rail sections to cause the free ends of the sections to lie in intimate engagement with the supporting ties at all times whereby the wheels of rolling stock in passing over the point will not cause a vibratory movement thereof, in view of the rigid mounting of the free ends of the switch point rail sections.

A further object of the invention is to construct the tie bar of the switch point rail sections, known in the art as tie bar No. 1, with the switch points carried thereby with the tie bar being capable of adjustment relative to the supporting ties and adjacent rails so that the switch points may be adjusted to substantially frictionally engage the ties over which the switch points move so that the upper tread portions of the switch points will lie flush with the tread surfaces of the main rails.

With the above and other objects in view, the invention consists in the novel form, combination and arrangement of parts herein fully described and shown in the accompanying drawings, wherein like reference characters indicate similar parts throughout the several views.

In the drawings,

Figure 1 is a top plan view of a portion 40 of a railway track constructed in accordance with the present invention, tie rod No. 1 being illustrated with the present improvement thereon,

Fig. 2 is a cross sectional view of the track shown in Fig. 1 showing switch point rail sections carried by the tie bars illustrating the adjusting means for the tie bar to cause the switch points at their free ends to engage the ties, with the connecting rod removed,

Fig. 3 is a top plan view thereof, and

Figs. 4 and 5 are fragmentary detail sectional views taken on lines IV-IV and V-V respectively of Fig. 2 showing the screw adjustment and pin guide between cooperating parts of the tie bar.

In the art to which this invention pertains, switch point rail sections after continuous use develop loose connections at their hinged ends or heels which permit a vibratory free movement of the opposite ends of the switch points and in the ordinary switch point at present in use and maintained in perfect working order, there is at least one-eighth inch loose play at the points and this degree of movement of the switch point increases to a swinging movement of three-fourths of an inch or more.

The wheels of the rolling stock in passing over the switch points if approaching at the heel end, cause the points to swing upwardly and when the wheels approach the free end of the switch points, the same are again moved downwardly into striking engagement with the supporting ties, thus causing an unusual wear upon the switch points to increase the longevity thereof. The present device overcomes this difficulty by the provision of a novel form of tie bar known in the art as tie bar No. 1, the switch points being connected to the tie bar and movable therewith. The opposite ends of the tie bar which extend beneath the opposite end main rails is of extensible construction, screw devices causing a separation of the extensible ends of the tie bar, one section of the extensible end engaging the bottom face of the main rail base with the other section of the extensible end being moved downwardly therefrom which in turn lowers the central connecting portion of the tie bar and with said connecting portion the switch points. With this operation, the free ends of the switch points are moved downwardly into positive engagement with the supporting ties so that vertical movement of the free end of the switch point relative to the tie will be prevented with the result that the upper face of the switch point will lie flush with the rolls of the main rail.

Referring more in detail to the accompanying drawings, there is illustrated a tie 6 of any preferred construction supporting the bases of the rails 7 secured thereon in any preferred manner as by headed spikes 8 engaging base flanges 9 thereof. A pair of switch point rail sections 10 are connected by the usual form of tie bars 11 spaced from the free ends thereof and known in the art as tie bars No. 2 while the improved form 105 of tie bar 12, known as tie bar No. 1 connects the free ends of the switch point rails.

Tie bar No. 1 is shown more clearly in Figs. 2 to 5 and includes a central portion 13 extending between the rails 7 and adjacent the tie 6 with the opposite ends thereof downwardly offset to provide parallel extensions 14 underlying the bases 9 of the rails. A plate 15 is arranged between the rail base 9 and the offset portion 14 of the tie bar and carries adjacent each end thereof 10 a downwardly directed pin 16 extending through an opening 17 provided in the tie bar offset 14 as clearly shown in Figs. 2 and 5 whereby the relative movement of the tie bar ends 14 and the plates 15 will be 15 guided.

The switch point rail sections 10 are of any ordinary construction and are secured to the tie bar section 13 inwardly of the rails 7 by angle members 18 having bolts 19 20 passing therethrough and through the switch points and tie bars.

The tie bar 12 is in reality carried by the switch points 10 which in turn are supported on the ties 6 so that an adjustment 25 of the sectional ends of the tie bars to cause a separation thereof will result in the lowering of the switch points 10 upon the ties for frictional contact therewith. The adjustment referred to is accomplished by 30 a pair of screws 20 passing through threaded openings in the offset extensions 14 of the tie bar with the upper ends thereof having a free thrust bearing with sockets formed in the bottom face of the plate 15 as shown 35 in Figs. 2 and 4, the central connecting portion 13 of the tie bar being maintained in adjusted position by the set nuts 21 upon the screw bolts 20. The lateral shifting of the tie bar with the switch points carried 40 thereby is accomplished by the connecting rod 22 extending to a point suitably spaced from the track for operation in any preferred manner.

Should the connecting heels of the 45 switch point rail sections become worn to cause a limited movement of the free ends of the switch points, this loose play may be taken up by adjusting the screw bolts 20 to force the plate 15 into engagement 50 with the bottom face of the rail base 9 with the subsequent lowering of the offset portions 14 of the connecting portions 13 of the tie bar 12 and with said offsets 14, the connecting portion 13 and the switch points 55 carried thereby thus hold the free ends of switch points substantially rigidly seated upon the ties to eliminate the free vibratory movement thereof caused by rolling stock passing thereover. With this device, 60 a fine adjustment of the parts is possible, pressure being exerted upwardly upon the bottom face of the rail base 9 and exerted downwardly by the switch point rail sections 10 on the upper faces of the ties, the 65 two forces working in opposite directions

to prevent relative movement of the switch points 10 and the tie 6. This invention is to be viewed in its broadest aspect and while the preferred form of the device is illustrated, it is to be understood that many 70 changes may be made therein such as the relative proportions of the different parts and substitutions of equivalents in so far as the operation thereof in the manner above described is obtainable. 75

What is claimed as new is:—

1. In combination, a pair of switch point rail sections, and a tie bar connecting the same, the tie bar being adjustable to cause the switch point rail sections to intimately 80 contact the supporting ties.

2. In combination, a railway rail, a switch point rail section associated therewith, a tie bar carried by the switch point rail section and coöperating with the rail to 85 cause the switch point rail section to frictionally engage the supporting tie.

3. In combination, a railway rail, a switch point rail section associated therewith, a tie bar carried by the switch point 90 rail section and extending beneath the railway rail, and means carried by the tie bar coöperating with the railway rail for causing a downward movement of the switch point rail section. 95

4. In combination, a railway rail, a switch point rail section associated therewith, a tie bar carried by the switch point rail section, a plate carried by the tie bar and arranged between the tie bar and railway rail and means for causing a separation of the tie bar and plate supported thereon whereby the switch point rail section is lowered onto the supporting tie. 100

5. In combination, a railway rail, a 105 switch point rail section associated therewith, a tie bar carried by the switch point rail section, a plate carried by the tie bar and arranged between the tie bar and railway rail, the plate and tie bar having co- 110 operating parts to guide the movements thereof and means for causing separation of the tie bar and plate supported thereon whereby the switch point rail section is lowered onto the supporting tie. 115

6. In combination, a railway rail, a switch point rail section associated therewith, a tie bar carried by the switch point rail section, a plate carried by the tie bar and arranged between the tie bar and railway rail, the plate and tie bar having co- 120 operating parts to guide the movements thereof, and thrust screws extending through the tie bars beneath the rail for engagement with said plate to cause the 125 plate to engage the base of the rail with the subsequent lowering of the tie bar and switch point rail section onto the tie.

In testimony whereof I affix my signature.
PHILIP CAMELI.
